UNITED STATES PATENT OFFICE

HOWARD E. WARD, OF INDEPENDENCE, MISSOURI

EXPANSION JOINT FOR BRIDGES AND THE LIKE

Application filed October 25, 1929. Serial No. 402,345.

This invention relates to expansion joints for bridges, viaducts, handrails and the like.

The objects of the invention are to produce an expansion joint which:—is flexible in all directions and hence adapted for service in any connection regardless of weather conditions or whether it is used on straightaway or curved portions of a roadway or handrail; may be composed of sections arranged end to end across a bridge or the like so that they may be installed or repaired, one at a time, without materially interfering with traffic; is provided with openings through which dirt may fall or be caused to fall by expansion and contractive actions of the joint under changing temperature conditions; is of such construction that interfering foreign particles of dirt, rock and the like upon the joint, shall be crushed or forced to non-interfering position by the expanding or contracting actions; in cold weather—when contraction is greatest—provides openings of maximum size to allow snow, ice, mud or clods to pass more readily; is adapted for use in conjunction with construction work of any material; has treads set diagonally with travel so that a vehicle wheel must bear on at least two or more treads on crossing the joint; is provided with spring tension bars to insure gradual expanding and retracting actions and to minimize noise produced by passing traffic.

Another object is to produce an expansion joint of strong and durable type and of attractive design so as not to detract from the appearance of a bridge or the like upon which it is used.

With the above mentioned objects in view the invention consists in certain novel features of construction and combinations of parts as hereinafter described and claimed; and in order that it may be fully understood, reference is to be had to the accompanying drawings, in which:—

Figure 1 is a plan view of a section of a joint embodying the invention, and the adjacent supporting roadway base of a bridge or the like; the joint being shown in what may be termed its normal condition in seasons of high temperature.

Figure 2 is a fragmentary plan with the tread elements of the expansion joint and the base of the roadbed omitted.

Figure 3 is a fragmental plan view showing the joint more widely opened, a condition which obtains in seasons of low temperature.

Figure 4 is an inverted plan view of the expansion joint element as disclosed by Figure 1, but on a larger scale.

Figure 5 is a cross section of the construction on a larger scale than Figure 4, the section being on the line V—V of Figure 1.

Figure 6 is a central vertical longitudinal section on the same scale as Figure 5.

Figure 7 is a detail perspective view of one of the tread members.

Referring to the drawings in detail, 1 indicates adjacent sections of the base and 2 the surfacing composition of the roadway base of a bridge or the like; said sections being spaced apart across the entire width of the structure for the accommodation of an expansion joint structure embodying the invention, which may, as a unit, extend from one side of the bridge to the other or may, and preferably will, be composed of sections arranged end to end across the bridge, and rigidly fixed in any suitable manner to the walls formed by the base. At opposite sides of the space are parallel connecting bars 3, preferably of angle type as shown and extending continuously by preference, from one side of the bridge to the other, the surfacing composition preferably overlying the upper edges of the inner or vertical arms of the connecting bars.

The connecting bars, at suitable intervals, are equipped with headed rivets or bolts 4, extending through filler tread bars 5, which fit flatly against the inner sides of the respective connecting bars 3, and the inner edges of the surface composition 2, and lie flush with the surface of the latter, these filler tread bars being formed at their upper edges, at regular intervals, with inwardly projecting and substantially V-shaped lugs or projections 6. Fitting also on the rivets or bolts 4 and flatly against the inner sides of the filler tread bars and spaced a suitable distance below the

lugs or projections 6, are spacers 7, tapered to a point at their upper ends. These spacers are shaped as explained to provide openings which facilitate the downward passage or escape of foreign matter, such as lumps of mud, snow or ice, which might otherwise accumulate or lodge under the lugs or projections 6 and interfere with the freedom of play or movement of certain links or tread members 10 hereinafter described.

Mounted also on the bolts or rivets and disposed parallel with but spaced from the filler tread bars 5, by the spacers 7, are angle bearing bars, the same comprising vertical arms 8 fitting on the bolts at the respective side of the joint for the full length of a section. The other arms 9 of said angle bearing bars, are horizontal and project inwardly, and the upper sides of said arms lie in about the same 15 horizontal plane as the upper ends of the points of the spacers 7, and said arms 9 are provided at points about midway between the lugs or projections of the filler tread bars, with diagonal slots 10, the slots of the respective arms being parallel. The slots of each arm are parallel with the slots of the other arm when the joints are expanded or contracted in a lateral direction only, that is, in the direction of the length of the bridge or 20 structure. If there is expansion or contraction or twisting of the bridge transversely of the roadway, the expansion joint accommodates such condition, but in such event the arms 9 may assume almost imperceptible converging relationship transversely of the structure, in one direction or the other, in which event the slots 10 of the bars would be drawn slightly out of parallel relationship.

The said arms 9 are also provided between 25 the diagonal slots thereof with longitudinal series of slots or openings 11, these slots having no particular function as regards the action of the expansion joint other than reducing weight and providing openings through which dirt, stones, ice, snow and water may fall, and it will also be apparent that the space between the horizontal arms 9 of the angle bearing bars also provides for the escape of foreign particles or matter as above suggested with reference to the last mentioned slots or openings. It will also be noted that the spaces between the arms 9 and lugs 6, communicate with the openings between the spacers 7 and the filler tread bars and the angle bearing bars, which openings as hereinbefore pointed out, provide for the fall or escape of such foreign particles.

Extending diagonally across the space between the angle bearing bars and resting 30 upon the arms 9 thereof, are links or tread members 12, each link or tread member having pins 13 near opposite ends, depending through diagonal slots 10 of the two angle bearing bars, the links extending at angles 35 approximately conforming to the angle of

the said slots and conforming in contour at their ends approximately to the contour of the upper inner edge of the filler tread bars, and said ends of the tread links are preferably roughened or toothed as at 14 (shown only on two of the tread links—see Figure 1), so that they may more readily break up or crush clods, lumps of snow or ice or other small foreign particles which may lodge between them and the filler bars, as the links 75 change their angular position under approaching and receding movements of the connecting bars incidental to expansion or contractive actions of the bridge or other structure.

To retain the diagonal tread links in position, cotter pins 15 or the like, extend through the depending pins, and to prevent the links jumping upward and downward under vibration of the bridge and thus producing an undesirable rattle or clicking noise, spring metal washer bars 16 are fitted on the pins between the cotter pins and the horizontal arms of the connecting or bearing bars. The spring metal washer bars are bowed downwardly between adjacent pins 13, of each longitudinal series thereof, so that by exerting upward pressure on the rigid angle bearing bars and downward pressure on the cotter pins, the links will be held by a yieldingly applied force down upon the said bearing bars.

In operation, assuming that the parts are disposed as indicated by Figure 1, and that a cold snap occurs which effects contraction of the sections of the bridge base and paving between the expansion joints, it will be apparent that the expansion spaces will be increased in width, and this will be true if the contraction of the bridge sections is equal or unequal. Under this increase in width of the expansion joint space, the space between the inner edges of the arms of the angle bearing bars will be increased and the angle of the tread links will be slightly changed or lessened. Under such conditions—compare Figures 2 and 3—the distance between diagonal slots engaged by the pins of particular tread links, will be slightly changed, the pins of such links moving in the slots to accommodate the changed relation of the angle bearing bars, and it will be obvious that if there is lateral expansion, that is expansion crosswise of the bridge but longitudinal of the joint, the relation between the angle bearing bars and the links will be still further changed. The connections have play allowing for movement in any direction or in more than one direction at the same time, it being conceivable that there may be concurrent distortion of the bridge laterally and longitudinally not only from changing temperature conditions but from stresses imposed under heavy loads.

From the above description, it will be ap-

parent that I have produced an expansion joint structure embodying the features of advantage enumerated as desirable in the statement of the objects of the invention, and
5 that the structure is susceptible of modification in various particulars within the principle of construction and mode of operation involved and therefore within the spirit and scope of the appended claims.

10 I claim:—

1. An expansion joint structure comprising a pair of spaced bearing bars and a plurality of diagonally arranged spaced tread links bridging the space between and carried by the bearing bars and having a loose connection with the latter.

15 2. An expansion joint structure comprising a pair of spaced bearing bars, a plurality of diagonally arranged spaced tread links bridging the space between and carried by the bearing bars and having a loose connection with the latter, and spring tension means exerting force tending to hold the bearing bars and links flatly together.

20 25 3. An expansion joint structure comprising a pair of spaced bearing bars and a plurality of diagonally arranged spaced tread links bridging the space between and carried by the bearing bars and having pin and slot connections with the latter.

30 35 4. An expansion joint structure comprising a pair of spaced bearing bars, a plurality of diagonally arranged spaced tread links bridging the space between and carried by the bearing bars and having pin and slot connections with the latter, and spring tension devices engaging and holding the bars and links flatly together.

40 45 5. An expansion joint structure comprising a pair of spaced bearing bars, a plurality of diagonally arranged spaced tread links bridging the space between and carried by the bearing bars and having a loose connection with the latter, and a pair of spaced tread bars rigid with and outward of the bearing bars and provided respectively with inwardly-projecting longitudinally-spaced lugs overlying the bearing bars and lying flush with the upper surface of and opposite the spaces between adjacent links.

50 55 6. An expansion joint structure comprising a pair of spaced bearing bars, a plurality of diagonally arranged spaced tread links bridging the space between and carried by the bearing bars and having a loose connection with the latter, and a pair of spaced tread bars rigid with and outward of the bearing bars and provided respectively with inwardly-projecting longitudinally-spaced lugs overlying the bearing bars and lying flush with the upper surface of and opposite the spaces between adjacent links; and teeth projecting into each space between the end of a link and the adjacent tread bar and bearing a rigid relation to one of said elements.

7. An expansion joint structure comprising a pair of spaced bearing bars, a plurality of diagonally arranged spaced tread links bridging the space between and carried by the bearing bars and having a loose connection with the latter, tread bars rigid with and spaced outward from the bearing bars, and a longitudinal series of spaced fillers rigid with and between each pair of bearing bars and tread bars.

75 8. An expansion joint structure comprising a pair of spaced bearing bars, a plurality of diagonally arranged spaced tread links bridging the space between and carried by the bearing bars and having a loose connection with the latter, tread bars rigid with and spaced outward from the bearing bars, and a series of spaced fillers rigid with and between each pair of bearing bars and tread bars; said tread bars being provided with longitudinally-spaced inwardly-projecting lugs overlying the bearing bars and spaced from and lying flush at their upper sides with the upper sides of the links.

85 9. An expansion joint structure comprising a pair of suitably supported spaced connecting bars, a pair of tread bars secured flatly against and projecting higher than said connecting bars and provided at their upper edges with uniformly-spaced inwardly-projecting lugs, angle shaped bearing bars paralleling and bearing a rigid relation to the connecting and the tread bars and underlying and spaced from the lugs of the latter, upwardly-tapering longitudinally-spaced fillers between the tread bars and bearing bars, diagonally arranged tread links bridging the space between and resting upon the bearing bars and having pin and slot connections therewith, the links being spaced at their ends from the tread bars and from the lugs thereof, and means for yieldingly resisting upward movement of the tread links with respect to said bearing bars.

95 10. In a structure of the character described, an angle shaped bearing bar provided in one arm with a longitudinal series of spaced slots and with a longitudinal series of parallel diagonal slots, the diagonal slots and first-named slots occurring alternately along the length of the bar.

105 11. In a structure of the character described, a tread bar provided at its upper end and at one side, at uniform intervals, with horizontal lugs of substantially V-form.

120 12. In a structure of the character described, a skeleton tread link of substantially rhomboidal contour and provided on its major axis and at equal distances from its ends with depending cylindrical pins.

125 13. An expansion joint structure comprising a pair of substantially parallel spaced bearing bars capable of movement directly toward and from each other, a plurality of tread links bridging the space between and carried

by the bearing bars, and connections between the opposite ends of each link and the respective bearing bar so arranged that as the bearing bars approach or recede in a direct line the links are caused to rotate on said connections.

In testimony whereof I affix my signature.
HOWARD E. WARD.
